US00D972614S

(12) **United States Design Patent** (10) **Patent No.:** **US D972,614 S**
(45) **Date of Patent:** **** Dec. 13, 2022**

(54) **SOLAR BACKUP CAMERA**

(71) Applicant: **Jiying Wang**, Guangzhou (CN)

(72) Inventor: **Jiying Wang**, Guangzhou (CN)

(**) Term: **15 Years**

(21) Appl. No.: **29/839,295**

(22) Filed: **May 19, 2022**

(51) **LOC (13) Cl.** **16-01**

(52) **U.S. Cl.**

USPC **D16/200**

(57) **CLAIM**

The ornamental design for a solar backup camera, as shown and described.

DESCRIPTION

FIG. 1 is a perspective view of a solar backup camera showing the claimed design;

FIG. 2 is a top plan view thereof;

FIG. 3 is a left side elevational view thereof;

FIG. 4 is a rear elevational view thereof;

FIG. 5 is a right side elevational view thereof;

FIG. 6 is a front elevational view thereof;

(Continued)

FIG. 7 is a bottom plan view thereof; and,
FIG. 8 is another perspective view thereof.

1 Claim, 8 Drawing Sheets
